UNITED STATES PATENT OFFICE.

AMOS L. WHITE, OF LEXINGTON, MICHIGAN, ASSIGNOR OF ONE-HALF TO RUDOLPH PAPST,
OF LEXINGTON, MICHIGAN.

FASTENING MEANS.

No. 873,692.

Specification of Letters Patent.

Patented Dec. 10, 1907.

Application filed April 9, 1906. Serial No. 310,805.

To all whom it may concern:

Be it known that I, AMOS L. WHITE, a citizen of the United States, residing at Lexington, in the county of Sanilac and State of Michigan, have invented new and useful Improvements in Fastening Means, of which the following is a specification.

This invention relates to fastening means for separately securing the free ends of shoe laces and the like, and has for an object to provide a device of the class embodying new and improved features of security, strength, convenience, and reliability.

A further object of the invention is to provide a fastener of the class described, embodying resilient fingers of improved form for engaging and retaining the ends of lacing cords and to be attached to shoes or similar articles of apparel.

With these and other objects in view the invention comprises certain novel constructions, combinations and arrangements of parts, as will be hereinafter fully described and claimed.

In the drawings:—Figure 1 is a perspective view of a shoe with the improved fastener associated therewith. Fig. 2 is a perspective view of the fastener disconnected from a lacing device. Fig. 3 is an enlarged perspective view of the device applied to a part of a shoe. Fig. 4 is an end view of the fastener with lace applied.

Like characters of reference designate corresponding parts throughout the several views.

The fastener forming the subject-matter of this application is adapted for application to any usual article of apparel, customarily laced as the shoe shown at 1. In its preferred embodiment the fastener comprises a plate 2 slotted longitudinally throughout a portion of its length, to form three fingers, 3, 4 and 5.

The plate 2 is secured to the garment in any approved manner, as by the rivets 6 and 7 and the fingers 3 and 4 are so curved as to conform to the shape of the garment and bear 45 resiliently upon the surface thereof. The finger 5 is bent backwardly upon the plate 2 to form a rearwardly opening hook proportioned to engage any usual lace as the cord 8.

As illustrating the preferred manner of 50 using the improved fastener, the lace 8, in Fig. 1, is shown as hooked over the rearwardly extending finger 5 and brought forward and slipped beneath the resilient finger 4. Used in the manner described the finger 55 3 is idle and is employed only when the fastener is used upon the opposite side of the garment and in reversed position.

While the manner of using the fastener illustrated in Fig. 1, is the preferred manner, 60 it is to be understood that the improved fastener may be employed in any other improved manner and to engage the lace otherwise than as shown.

What I claim is:—

In a lace fastener, the combination with a shoe upper, of a plate having three fingers formed by two parallel cuts projected from one side partly across said plate, and with the two outer fingers bent to engage the upper 70 adjacent their ends and spaced from the upper intermediate their lengths, and with the middle finger bent backwardly and curved toward the plate adjacent its end, and curved and spaced from the plate intermediate its 75 length.

In testimony whereof I affix my signature in presence of two subscribing witnesses.

AMOS L. WHITE.
